UNITED STATES PATENT OFFICE.

KARL RÖGER, OF BERLIN, GERMANY, ASSIGNOR TO MERGENTHALER LINOTYPE COMPANY, A CORPORATION OF NEW YORK.

TYPOGRAPHICAL COMPOSING AND DISTRIBUTING MACHINE.

1,212,561.

Specification of Letters Patent. Patented Jan. 16, 1917.

Application filed July 8, 1914. Serial No. 849,634.

To all whom it may concern:

Be it known that I, KARL RÖGER, a subject of the German Emperor, residing at 33 Tel-towerstrasse, Berlin, in the Empire of Germany, have invented new and useful Improvements in Typographical Composing and Distributing Machines, of which the following is a specification.

It has already been proposed, for the purpose of bringing into operative position the individual magazines of a plurality of superposed magazines in a matrix composing and line casting machine, to move these magazines in a common frame as a single entity, or on special frames, one for each magazine or one for each group of magazines, the said frames being guided rectilinearly or turnable curvilinearly about pivotal axes. The magazines can be guided rectilinearly only if all the magazines have a common distributor, because movement of the magazines, or, as it is hereinafter termed, changing, can be done only after the distribution of the last previously composed line has been completed. When, however, the magazines are adjustable curvilinearly, each magazine may have a special distributor which remains in constant operative relationship to the upper end of that magazine, while the lower ends of the magazines are alternately brought into operative relationship to a common assembler plate entrance. As, in these machines, matrices can be distributed into a magazine last previously in use, even after a change of magazines has been effected, the said machines must be so constructed that the position of the distributing devices relatively to their magazines, for all positions of the latter, will always be such as to insure the distribution proceeding without interruption.

When turnable or curvilinearly adjustable magazines are used, it has heretofore been found difficult to embody in a machine the last mentioned disposition, especially in cases in which more than two magazines are employed. It has already been proposed to arrange the pivotal axis of a magazine as high as possible and directly below the distributor rail, but even this arrangement does not in all cases give a satisfactory result.

The invention remedies the aforesaid defect by causing the magazines, when being

changed into their respective operative positions, to move in paths other than the ordinary rectilinear or truly circular path, this result being attained by guiding the magazines collectively, or independently, or in groups, in or by cams in such a manner that the movement of the magazines to bring one into operative position disturbs, to the minimum extent, the relationship of all of the other magazines to their respective distributors.

The invention will now be described by reference to the accompanying drawings, the nine figures of which show in side elevation, and more or less diagrammatically, nine different constructional forms of the invention.

Throughout the several figures of the drawings, like reference numerals are used to indicate like or corresponding parts.

In all the constructional forms represented in the different figures, 1, 1^a, 1^b, etc., are the magazines, 2 the assembler plate entrance, between the partitions of which (not shown in the drawings) the matrices released from the lower end of the magazine then in operative position, descend, 3 are the escapement rods operated, as ordinarily, by the keyboard mechanism, 4 are the escapements which normally retain the matrices in the magazines and release them therefrom when operated by the escapement rods 3, and 5 is the distributor mechanism. Each magazine 1 is provided with its own distributor mechanism, so that distribution into any of them can take place regardless of which magazine is, for the time being, in working position.

6 are the magazine entrances which move with the magazines when they are adjusted from one to another position, and of which there is one for each magazine.

In the constructional form represented in Figure 1, the magazines 1, 1^a, are supported on a common magazine frame 7 carrying at each side thereof, rollers 8, 9, 10, of which the rollers 8, pivoted directly on the said magazine frame 7, engage with guides or grooves 11, and the rollers 9 and 10, pivoted at its upper part, travel along curved tracks 12, both the guides 11 and tracks 12 being cam-shaped or non-circular and fast to or integral with the machine frame 13. The

shape of the guides 11 and tracks 12 is such that, when the magazines are changed or, in other words, adjusted for bringing any one into operative position, the magazine entrances 6 will be shifted bodily or about a changing axis so as to always retain, relatively to the distributor mechanism, positions most favorable to a continuance of uninterrupted distribution.

- 10 The guides 11 constitute virtually cam grooves which serve to move the magazines both rearward and forward by engaging with the rollers 8 on diametrically opposed lines, and the magazines 1, 1^a, and magazine frame 7 are so locked together that during the changing operations, they move only as a single entity.

15 The magazines, for effecting the aforesaid changing, may be moved by any convenient means; in Fig. 1 a link 14 is indicated for the purpose, this link being itself operated by any convenient means, which, however, constitute no part of the present invention.

20 In Fig. 1, the magazines 1, 1^a, and magazine frame 7 are shown in full lines in the position in which the magazine 1 is in operative register with the assembler plate entrance 2, and in dot and dash lines in the position in which the magazine 1^a is in operative register with the said assembler plate entrance 2.

25 The arrangement shown in Fig. 2 is substantially similar to that illustrated in Fig. 1, the only material feature of difference residing in the fact that the tracks 12 form, in this example, the underside of what are virtually cam grooves, and further, in the fact that the magazine frame 7 is guided by additional rollers 8^a, each of which, like its companion roller 8, is pivoted to a plate 15 attached to the respective side of the magazine frame 7.

30 The arrangement shown in Fig. 3 differs from that last described in respect only of the fact that the upper end of the magazine frame 7 is guided on each side by only a single roller 9, which, like each of the rollers 9, 10 of the arrangement shown in Fig. 2, is guided in a cam groove, the lower part of which is mechanically equivalent to the before described track 12. Fig. 3 also illustrates an angularly adjustable cam 16 as a means for adjusting the magazines 1, 1^a, this cam being arranged to act on a roller 17 pivoted to the underside of the magazine frame 7.

35 In the constructional form represented in Fig. 4, the magazine frame 7 is guided at each side by a single roller 9 traveling over a track 12, as in Fig. 1, and near its lower end by a single roller 8 traveling within a cam groove 11, also as represented in Fig. 1. This arrangement also shows as an example another means for adjusting the magazines 1, 1^a, the said means consisting of an

angularly movable wiper arm 18 which engages with a roller 17 pivoted to the underside of the magazine frame 7.

40 In each of the four before described constructional forms, it has been assumed that the guide rollers, cams and tracks have been arranged symmetrically on both sides of the magazines 1, 1^a, but it is to be understood that instead of that arrangement there may be symmetry only as regards the upper or lower of such guiding devices, the other said devices being replaced by a central roller and track.

45 In all of the foregoing arrangements, the magazines 1, 1^a and magazine frame 7 are locked together, so that, as previously described with reference to Fig. 1, they all move as one single entity during the operation of changing, but in each of the five constructional forms now to be described, the magazines are arranged so that, during the said operation of changing, one or more of them can move relatively to the other magazines.

50 In the arrangement represented in Fig. 5, each of the magazines 1, 1^a, is mounted on a separate magazine frame 7, 7^a, and each of these frames is provided with separate guiding devices which are virtually similar to those previously described, thus, for example, the frame 7, as in Fig. 1, has pivoted to its two sides rollers 8 which engage with the cam grooves 11 and with rollers 9, 10, traveling over stationary tracks 12, and the magazine frame 7^a is, on each side, provided with rollers 8^a which engage with cam grooves 11^a, and at its upper end, with rollers 9^a and 10^a, which travel over a stationary track 12^a.

55 Beneath the magazine frame 7 there is provided a lever or frame 19 (hereinafter referred to as a lever), pivoted at 20 to the main frame 13 of the machine, this lever carrying at its two sides two upstanding plates 21, each of which is formed with two rails,—represented in dotted lines in Fig. 5, for engaging with two rollers 22, 23, respectively, pivoted to the respective magazine frames 7, 7^a. The lever 19 is turned angularly upon its pivot 20 by means of a link 14 or any other suitable device, and when so lifted it, at the same time, raises the magazine frames 7, 7^a and magazines 1, 1^a, through the engagement of the rollers 22, 23 with the respective rails on the upstanding plates 21.

60 The constructional form represented in Fig. 6 is somewhat similar to that shown in Fig. 5, the only substantial difference being that in this arrangement the lever 19 is dispensed with and the magazine frame 7 itself fulfills the function of that lever, inasmuch as the said magazine frame 7 is provided with upstanding plates 21 having rails over which the rollers 23, pivoted to the magazine frame 130

7^a, are capable of traveling. In this arrangement, as in Fig. 5, the magazine 1 is connected to the magazine frame 7 in such manner that, during the changing operation, it has no movement relatively thereto.

In Fig. 7, the present invention is shown applied to a machine having three magazines, the uppermost of which, during the operation of changing, moves relatively to the two lower magazines, which latter, during that same operation, move as one entity. In this arrangement, the magazines 1, 1^a, are supported on a common magazine frame 7 which, like the corresponding magazine frame shown in Fig. 1, is guided by rollers 8, 9 and 10, of which the rollers 8 travel in cam grooves 11 and the rollers 9 and 10 travel in cam grooves 12, the lower part of each of which constitutes a cam track similar to the track 12 in Fig. 1. The magazine 1^b is supported on a magazine frame 7^a, which is guided in a similar manner to that appertaining to the magazine frame 7, by three rollers 8^a, 9^a and 10^a, at each side, the rollers 8^a engaging cam grooves 11^a, and the rollers 9^a and 10^a traveling in cam grooves 12^a. The magazine frame 7^a is, at its underside, provided with one or more rollers 23, which bear directly on the top plate of the magazine 1^a, and the arrangement is such that when, through, say, the link 14, the magazine frame 7 is raised or lowered, the magazines 1 and 1^a will move as if in one piece with that magazine frame, and the magazine 1^b will be correspondingly raised or lowered, but, in addition, move relatively to the magazine 1^a in a forward or backward direction, the rollers 23 allowing for perfect freedom to move in that direction.

In Fig. 8, the invention is shown applied to a machine having four magazines arranged in two groups, each comprising two of such magazines. Each of these groups, during a changing operation, moves together with its magazine frame 7 or 7^a as a single entity, these two entities being capable of independent motion in a manner similar to the motion of the magazine 1^b relatively to the magazines 1^a and 1 of the arrangement last previously described. Each of the magazine frames 7 and 7^a is guided in substantially the same manner as the equivalent magazine frame shown in Fig. 7; consequently no further description thereof is herein considered to be necessary. This arrangement, however, differs from that shown in Fig. 7 in that the magazine frame 7^a is not supported directly upon the top of the magazine 1^a, but is supported by the magazine frame 7, to which it is, at each side, connected by a pivoted link 24. It will thus be seen that when the group comprising the magazine frame 7 and magazines 1 and 1^a is moved, say by the link 14, the

group comprising the magazine frame 7^a and magazines 1^b and 1^c will, through the links 24, be moved simultaneously therewith, and any motion of the last named group due to the curvature of the cam grooves 11^a and tracks 12^a will be freely allowable by reason of the pivoted links 24 which, during that operation, turn about the pivots by which they are respectively connected to the magazine frames 7 and 7^a.

In the constructional form represented in Fig. 9, the magazine frame 7 is arranged to move in a truly circular path, as distinguished from the curvilinear, but non-circular path, common to all the examples previously described. This result is attained, as in arrangements heretofore proposed, by pivoting the said magazine frame 7 upon studs or stationary pivots 25 situated as near as possible to the underside of the respective distributor. By this arrangement, when the magazine frame 7 is moved about the axis of the pivots 25, that frame and the magazines 1, 1^a, carried thereby, move as a single entity in a circular path. The upper group in this present example, which embraces the magazine frame 7^a and magazines 1^b and 1^c, is guided, as in the last preceding example, by three rollers 8^a, 9^a and 10^a at each side thereof, these rollers 95 engaging with cam grooves in identically the same manner as do the corresponding rollers of the arrangement shown in Fig. 8. The last mentioned group, comprising the magazines 1^b and 1^c, is moved during the changing operation through rollers 23, which bear upon the top plate of the magazine 1^a, the said rollers allowing that group during the said operation to move independently of the group comprising the magazines 1 and 1^a.

Although no special description has heretofore been given of the distributor mechanism of the various arrangements illustrated, it will be well understood that, as shown in the different drawings, this mechanism is varied according to the number of magazines to be served by it.

Having described my invention, I declare that what I claim and desire to secure by Letters Patent is:

1. In a typographical composing and distributing machine, the combination with a magazine, and means operative to move that magazine flatwise, of fixed cam-shaped guiding means adapted to convert that motion into a curvilinear motion other than a circular one.
2. In a typographical composing and distributing machine, the combination with a magazine, and means operative to move that magazine flatwise, of fixed cam-shaped guides adapted to guide the magazine curvilinearly otherwise than circularly.
3. In a typographical composing and dis-

tributing machine, the combination with a magazine supporting frame, and means for moving the frame up and down in the machine, of fixed cam-shaped guiding means 5 adapted to convert that motion into a curvilinear motion other than a circular one.

4. In a typographical composing and distributing machine, the combination with a plurality of superposed magazines, capable 10 of moving fore and aft independently of each other, and means operative to move those magazines flatwise, of fixed cam-shaped guides adapted to guide each magazine curvilinearly otherwise than circularly 15 and independently of another magazine.

5. In a typographical composing and distributing machine, the combination with a plurality of superposed magazines some of them arranged in a group independently of 20 another of them, the group being movable fore and aft as a single entity independently of the magazine outside of that group, and means operative to move the magazines flatwise, of fixed cam-shaped guides adapted 25 to guide the group of magazines and the magazine outside that group, in respectively different curvilinear paths other than circular paths.

6. In a typographical composing and distributing machine, the combination with a plurality of superposed magazines arranged in a plurality of superposed groups movable fore and aft independently of each other, and means operative to move the groups of 35 magazines flatwise, of fixed cam-shaped guides adapted to convert the flatwise movement of each group independently of the movement of another group, into a curvilinear movement other than a circular one.

7. In a typographical composing and distributing machine, the combination with a plurality of superposed magazines and a plurality of independently movable magazine frames on which they are supported, 45 and means operative to move those frames flatwise, of fixed cam-shaped guiding means adapted to convert the flatwise movement of each frame independently of the movement of another frame, into a curvilinear 50 movement other than a circular one.

8. In a typographical composing and distributing machine, the combination with a plurality of superposed magazines and a plurality of independently movable magazine frames on which they are supported, 55 and means operative to move those frames flatwise, of fixed guides, and rollers on the magazine frames engaging the guides, the

said guides being cam shaped so as to convert the flatwise movement of the magazines 60 thereon into a curvilinear motion other than a circular one.

9. In a typographical composing and distributing machine, the combination with a magazine and a magazine frame supporting 65 it, and means operative to move them flatwise, of fixed guides, and rollers on the magazine frame engaging the guides, the said guides being cam shaped so as to convert the flatwise movement of the magazine into 70 a curvilinear motion other than a circular one.

10. In a typographical machine, the combination with a plurality of distributors and a single assembling mechanism, of a plurality of intermediate magazines movably mounted so that one or another may be brought into operative relation to the assembling mechanism without disturbing their operative connection with the overlying distributors, and a system of fixed curved tracks or guides upon which the magazines are supported, the said tracks or guides being cam-shaped or non-circular so as to cause the magazines to shift bodily or about 85 a changing axis during their movement, for the purpose described.

11. In a typographical machine, the combination with a plurality of distributors and a single assembling mechanism, of a plurality of intermediate movable magazines, and curved tracks or guides upon which the magazines are supported at both their upper and lower ends, the curvature of said supporting tracks being such that movement of 95 the magazines thereon will locate one or another in operative relation to the assembling mechanism without disturbing the operative connection of the magazines with the respective distributors.

12. In a typographical machine, the combination of a plurality of magazines, a supporting frame therefor provided at its upper and lower ends with rollers, and fixed curved supporting guides upon which said rollers track, the curvature of said guides being such that the tracking of the rollers thereon will cause the magazines to turn about a changing axis, for the purpose described.

In witness whereof I have hereunto set my hand in the presence of two witnesses.

KARL RÖGER.

Witnesses:
